UNITED STATES PATENT OFFICE.

WILLIAM E. PALMETER, OF ELMWOOD, NEBRASKA.

MIXING APPARATUS.

Application filed July 18, 1922. Serial No. 575,800.

To all whom it may concern:

Be it known that I, WILLIAM E. PALMETER, a citizen of the United States, residing at Elmwood, in the county of Cass and State of Nebraska, have invented certain new and useful Improvements in Mixing Apparatus, of which the following is a specification.

This invention appertains to improvements in mixing apparatus generally, and 10 more particularly to a type thereof adapted for the mixing of cement or the like for use in building operations of various classes and descriptions.

The principal object of the invention is to 15 provide for an apparatus of the class mentioned, and one of a mechanically refined construction and arrangement, such as will render the same readily portable from one point of use to another, durable and efficient 20 under any and all conditions of its operation or use, and comparatively inexpensive to manufacture.

Another object of the invention is to provide for a mixer of the type as hereinbefore 25 characterized, and one involving an operating means designed to impart a continuous action or rotation to the mixer proper, regardless of its position of adjustment and use, and in a manner to be substantially 30 smooth and even in its operation, and practically free from all vibrations such as otherwise causes undue wear and tear on the parts thereof.

With the foregoing and other equally important objects in view, the invention resides in the certain novel and useful construction and arrangement of parts as will be hereinafter more fully described, set forth in the appended claim, and illustrated in the 40 accompanying drawings, in which:—

Figure 1 is a side elevation of a preferred embodiment of the invention,

Fig. 2 is a top plan view thereof,

Fig. 3 is a front elevation of the same,

Fig. 4 is an enlarged vertical transverse section taken on the line 4—4 of Fig. 2,

Fig. 5 is a top plan view of the container or mixer, per se,

Fig. 6 is a fragmentary vertical section 50 taken on the line 6—6 of Fig. 4, and

Fig. 7 is a similar section taken on the line 7—7 of Fig. 4.

Referring to the drawings, wherein similar characters of reference designate corresponding parts throughout the several views thereof, the main frame of the mixer is pref-

erably formed of a suitable length of metal stock bent substantially U-shaped to provide oppositely disposed vertical leg portions forming standards 10 and 10', and a lower connected horizontal portion or base 11. To the outer sides of the standards 10 and 10' are bolted, as at 12, supports 13, which have their lower ends bent outwardly in the plane of the lower connected portion 11 of the frame, and formed to provide spindles 14 for the mounting thereon of the wheels 15, which are retained in position by means of cotter pins or the like 16. Bolted as at 17 to the base 11 of the main frame and immediately inward of the opposite ends thereof, are the free ends with respect to the opposite leg portions 18', 18'', of the inner yoke shaped portion of a tongue 18, which has its outer end extended laterally in opposite directions to provide a hand gripping portion 19. The forward end portion of the tongue 18 is angularly bent in a downward direction, to have the hand gripping portion 19 thereof rest on the ground, when the main frame is disposed in its operative position, i. e. slightly inclined from the perpendicular. Disposed within the U-frame is a substantially V-shaped brace member, and which has its opposite leg portions 20 and 20' secured at their upper ends to the standards 10 and 10' by means of bolts or the like 21, and the lower portions thereof bolted as at 22 medially of the base 11 of the main frame. Secured at these upper ends to the standards 10 and 10', by the bolts 21, are forwardly projecting inclined brace members 23 and 23', which are secured at their lower ends, by means of the bolts 24, to the opposite leg portions 18' and 18'', respectively, of the yoke shaped inner portion of the tongue member 18. These brace members 23, 23', are adjustable and the adjustment is had by means of spaced openings 23'' being provided in their lower ends for selected engagement on the bolts 24.

The upper ends of the standards 10 and 10' are formed to provide enlargements in the form of open bearings 25 and 25', in the former is journaled a short pintle 26 and 105 in the latter a bearing sleeve 27, the pintle 26 and sleeve 27 provided means for pivotally supporting a substantially U-shaped tilting frame, which is formed from a length of flat metal stock bent to provide oppositely disposed leg portions 28' and 28'' and a curved base 28. The leg portions 28', 28'' at their

lower termini, are torsionally twisted, so that they will be disposed in spaced parallel relation, one with respect to the other. This tilting or pivoted frame normally depends 5 within the main frame from the pintle 26 and the sleeve 27, the pintle 26 being rigidly secured in right angular relation outwardly of the upper end of the leg portion 28', while the upper end of the leg portion 28'' is 10 formed with a circular opening loosely fitting on the bearing sleeve 27. This bearing sleeve 27 forms a housing for the journaling therein of a power shaft 29, on the outer end of which is keyed a power driven pulley 30, and on the inner end thereof is similarly keyed a worm gear 31, which is arranged in mesh with a worm wheel 32 keyed on the upper end of a vertically disposed shaft 33. This shaft 33 is journaled in a 15 housing portion 34 carried vertically of the pivoted frame in parallel relation to the leg portion 28'' thereof. The worm gear 31 and the worm wheel 32 are housed in an enlarged inner end portion 27' of the bearing sleeve 27, and to which the upper end of the housing portion 34 connects, while the lower end of the latter is secured as at 34' to a bracket 34'' attached to the base 28 of the tilting frame. The upper end of the shaft 33, is 20 journaled in a bearing plug 35, threaded into an opening formed in the upper side or end of the housing portion 34. The lower end portion of the shaft 33 is journaled in a bearing collar or bracket 36. Keyed on the 25 lower end of the shaft 33 is a beveled gear 37 arranged in mesh with a second beveled gear 38, which is keyed on one end of a horizontally disposed shaft 39. One end of the shaft 39 is journaled in a bearing sleeve 40, and at its other end in the end wall of a 30 housing 41 the latter incloses the shaft 39 and into one end thereof extends the bearing sleeve 40. That end wall portion of the housing 41 which supports one end of the shaft 39 being preferably in the form of a removable plug like body substantially as shown. Fastened on the opposite end of the shaft 39, is a worm gear 42, arranged in mesh with a worm wheel 43 carried at the 35 lower end of a mixer container operating shaft 44. This shaft 44 is journaled at its lower end in a bearing block 45, secured in position on the base 28 of the pivoted frame, and at an intermediate point, in a bearing 46, formed at the upper side of the housing 41, and bolted as at 47, to a cross bar 48, disposed horizontally between the lower ends of the leg portions 28' and 28'' of the pivoted frame 28, and is secured thereto by means of 40 bolts or the like 49. The upper end portion of the vertical shaft 44, projects for a distance above the bearing portion 46, and extends upwardly through the concentric aperture of an external boss 50, formed centrally of the bottom wall of the mixing 45

container 51, the latter being preferably of barrel-like form and open at its upper end substantially as shown. The extreme upper end of the shaft 44 terminates inwardly of the upper open end of the container or mixer 51, and has bolted thereto as at 52, a plurality of downwardly inclined brace rods or bars 53, which are secured at their lower ends to the inner face of the container as at 54, adjacent the bottom thereof. The upper end 75 of the shaft 44, has secured thereto a series of radially disposed mixer arms or rods 55, which are inclined slightly in an upward direction and are secured at their outer ends to the inner face of the container or mixer 80 in any suitable manner. It is to be noted of the housing portions 27', 34 and 41, that the same entirely enclose the shafting for transmitting power from the pulley 30 to the mixing shaft 44, and that the space therein may 85 be filled with a lubricant entirely surrounding the gear mechanism.

The pintle 26 which is journaled in the standard 10 is formed to provide a squared outer end portion 26' on, which is engaged a hand lever 56, for effecting the desired swinging movements of the frame 28, to move the container or mixer 51 to and from operative and dumping positions. The inner end of the hand lever 56 is formed with 90 a hook portion 57, engaged over a half moon segment 58, bolted as at 59, on the outer side of the upper end portion of the standard 10 immediately below the bearing portion 25 thereof. Pivoted as at 60' outwardly of the hooked end of the lever is a locking dog 60, which is operable through the medium of a push rod 61, disposed parallel to the lever with its upper end portion engaged for movement longitudinally 100 through a hand grip 62 carried at the outer end of the latter. The locking segment 58, is provided with notches 63, spaced along its outer or lower curved edge for the engagement therein of the dog 60, whereby 110 the mixer 51 may be held in any one of its several positions of operation.

In the operation of the device as thus constructed and arranged, the same may be readily pulled or pushed from one point to 115 another by the operator grasping the handle portion 19 of the tongue 18, and, when properly positioned, the pulley 30 will be belted to a suitable source of power (not shown). When positioned adjacent the point of use, the materials for the cement mixture will 120 be placed within the container or mixer 51, inwardly of the open end thereof, and preferably with the container or mixer disposed in its unlocked and vertical position, which 125 position it will naturally assume when the dog 60 is disengaged from one of the notches of the segment 58. The container will then be swung to one of its inclined positions and locked therein by the dog 60 engaging 130

in one or the other of the notches of the segment 58, after which power will be applied to the pulley 30 for the rotation of the container or mixer 51. When the mixing operation is completed, the mixed cement or other material will be readily dumped from the container or mixer 51, by the operator grasping the hand lever 56, and swinging the frame and container or mixer carried thereby on the axis formed by the sleeve 27 and the pintle 26, for the tilting of the container to a position whereby the contents will readily discharge from the open end thereof.

15 From the foregoing, it will be readily apparent that the invention provides for a simple and inexpensive construction and arrangement of mixing apparatus, one which may be readily moved about from point to point on a building or construction operation, and which is adapted for extreme ease in operation by a single operator if desired or necessary. It will also be obvious that, while a preferred embodiment of the apparatus has been described and illustrated herein in specific terms and details of construction and arrangement, various changes in and modifications of the same may be resorted to without departing from the spirit

of the invention, or the scope of the claim 30 appended hereto.

Having thus described the invention, what is claimed as new, is:—

20 A mixer for the purpose set forth comprising a main frame, a U-shaped tiltable frame arranged within the main frame and provided with a support, a mixing chamber mounted on said support, a power shaft support mounted at one side of the main frame for pivotally supporting one side of 35 the tiltable frame, a pintle projecting from the other side of the tiltable frame and pivotally mounted in the other side of said main frame for pivotally supporting the other side of the tilting frame within the 40 main frame, a power shaft journaled in the power shaft support, an operative drive connection between said power shaft and said container, a rack carried by the main frame, and an adjustable means connected 45 50 with said pintle and cooperating with said rack and adapted to shift said container at an angle and for maintaining it in its shifted position.

25 In testimony whereof, I affix my signature hereto.

WILLIAM E. PALMETER.
